UNITED STATES PATENT OFFICE

ALICE M. NURNBERG, OF PORT TOWNSEND, WASHINGTON

CIGARETTE HOLDER

Application filed December 17, 1928. Serial No. 326,527.

This invention relates to cigarette holders and aims primarily to provide an improved and novel type of cigarette holder, which is especially designed and adapted for restrainingly engaging the cigarette at any desired and selected point thereon, which permits placing of the cigarette directly between the lips of the smoker, the use of which effectually prevents staining or soiling of the 5 smoker's fingers, from which the cigarette stub is rapidly and expeditiously ejected without the necessity of touching such stub, which may be fabricated from any suitable material, which lends itself readily to variations in form and design, and which may be embellished in either a simple or elaborate manner as desired and found expedient.

Contemplated by the present invention is a cigarette holder embodying a stem fabricated from any suitable material, and embellished with any suitable design as desired; a tubular shank mounted upon one end of said stem; a resilient hook-shaped cigarette holding member rigidly secured to the outer 10 end of said tubular shank; a flexible member normally conforming to the shape of said holding member for ejecting the cigarette stubs therefrom; and means mounted within the tubular shank and operable by the finger 15 or thumb nail of the smoker for actuating the ejecting member to effect ejection of the stubs without the necessity of touching same; all of which are important objects and primary features of the invention and are to be co-related in the broad aim of enhancing the 20 efficiency of the device for general use.

The above, and additional objects which will hereinafter be more specifically treated are attained by such means as are shown in 25 the accompanying drawings, described in the following specification and then more clearly pointed out in the claims, which are appended hereto and form part of this application.

With reference to the drawings, in which 30 there is illustrated several embodiments of the invention, and throughout the several views of which like characters of reference designate similar parts:

Figure 1 is a front elevation of a cigarette 35 holder comprehended by the present inven-

tion, and of the type more particularly adapted for men smokers, certain parts of the same being shown in section for clarity of illustration.

Fig. 2 is a side elevation thereof with certain parts also shown in section. 55

Fig. 3 is an enlarged vertical medial section of the upper half portion of my cigarette holder, with its correlated cigarette stub ejecting member in a normally retracted position. 60

Fig. 4 is an enlarged fragmentary front elevation of the same, certain parts being broken away, and certain other parts being shown in section, also with the cigarette stub ejecting member illustrated in a fully advanced or stub ejecting position. 65

Fig. 5 is an enlarged horizontal section taken through line 5—5 of Fig. 4.

Fig. 6 is an enlarged fragmentary longitudinal section taken through line 6—6 of 70 Fig. 3.

Fig. 7 is a perspective view of my cigarette holder illustrating more particularly the manner of positioning a cigarette therein.

Figure 8 is a similar view of a slightly modified type of cigarette holder more particularly adapted for women smokers, and illustrating the preferred manner of holding 75 the device while smoking.

Fig. 9 is a similar view illustrating the 80 manner of ejecting a cigarette stub from the device, and

Fig. 10 is a fragmentary front elevation of a still further modified type of cigarette holder, which latter is not equipped with a 85 cigarette stub ejecting member.

Before taking up the detailed description of the drawings, a general exposition of the specific purposes, features, and functions of the cigarette holder evolved by the present 90 invention will be undertaken. Heretofore, it has been customary to fabricate cigarette holders in the well known tubular form or type. Unfortunately, however, these tubular holders are objectionable to a comparatively large number of smokers, inasmuch as such holders cool the smoke and positively and effectually prevent the smoker placing the cigarette directly in contact with the lips. 95 A further and serious objection to the tubu- 100

lar type of cigarette holders is that the same rapidly and readily become impregnated with nicotine and in a very short time become offensively and obnoxiously odorous. It is therefore, a primary aim, and object of this invention to provide a cigarette holder, wherewith the smoker may have direct contact with the cigarette, a feature which is deemed highly desirable by a great many smokers. A further primary aim and object of the invention is to provide a cigarette holder that cannot become impregnated or fouled with nicotine, thus eliminating the possibility of the same becoming offensive or obnoxious to the user.

Beginning the more detailed description of the invention by reference to the drawings, the numeral 11 designates a slightly tapered stem or handle, which may be fabricated from any suitable material, such as, wood, metal, jade or other semi-precious stone, composition, or the like, to the upper end of which is threadedly secured a slightly tapered tubular shank 12, preferably of metal, which shank extends upwardly from the stem 11 in axial prolongation thereto, and at its upper end terminates in the semi-spherical or rounded formation more clearly illustrated in Figs. 3 and 4.

Fixedly secured at its inner end, as by brazing or soldering, to the upper rounded end of the shank 12 is a relatively narrow hook-shaped resilient cigarette holding member 13, preferably fabricated from a thin strip of spring material, which strip is formed slightly arched, or concavo-convex in cross-section, as indicated at 14 in Fig. 6, and at its outer or free end is provided with an outturned terminal 15, for a purpose about to be described.

Rigidly secured, as at 16, to the terminal 15 is the outer end of a flexible cigarette stub ejecting member 17, which is preferably fabricated from relatively light spring wire, and is designed to normally and substantially conform to the shape or contour of the holding member 13, said ejecting member 17, when not in use, being adapted to seat within the concavity of the member 13 throughout its entire length, substantially in the manner illustrated in Fig. 6. The ejecting member 17 extends downwardly from the holding member 13 into the tubular shank 12 through an axially aligned aperture 18, formed in the semi-spherical upper end of such shank. The portion 19 of the ejecting member extending within said tubular shank is disposed in axially aligned or concentric relation therein, and is preferably formed of a slightly larger diameter, as shown in Figs. 6 and 7 for the purpose of stiffening the same. The material of the portion 19 at its lower end is bent at right angles, as indicated at 20, to extend outwardly through a longitudinally disposed slot 21 formed in the walls of the

tubular shank 12, and at its outer end is provided, exteriorly of said shank, with a button or head 22 for engagement, on occasion with the nail of the smoker.

To effectually and properly protect the member 13, when the device is not in use, I provide a cap 23, which is adapted to completely enclose or encase said member, in the manner more clearly shown in Figs. 1 and 2, to thereby positively prevent such member from catching in the pocket of the smoker.

To retain the device in the pocket of the smoker, or the like, I provide a spring clip 24, which is attached in a well-known manner to the handle 11, and is adapted to restrainingly engage the edge of such pocket.

In Figs. 3, 6 and 7 I have illustrated the manner of positioning a cigarette, designated by the numeral 25, within the device, and in Figs. 4 and 8 the manner of ejecting a cigarette stub 25' therefrom. In placing or positioning a cigarette in the device, the handle 11 is ordinarily held in the left hand, the thumb nail of which is employed to slightly depress the button 22, to thereby slightly spread or distend the member 13 and thus facilitate and expedite the placing of the cigarette therein with the right hand, substantially in the manner shown in Fig. 7, upon placing the cigarette 25 within the member 13, the button 22 is released to permit said member 13 to restrainingly engage the cigarette, as will be obvious and apparent. When the cigarette stub 25' is to be ejected, the device is ordinarily held in the right hand and the thumb nail of same employed to fully depress the button 22, whereby the ejecting member 17 and the holding member 13 are distended or expanded, as shown in Figs. 4 and 9, whereupon the stub 25' is ejected into an ash tray designated by the numeral 27.

In the slightly modified type of cigarette holder disclosed in Fig. 6, which type is particularly designed and adapted for use by women smokers, the handle 11 is illustrated as being embellished with a fanciful design, which latter may be varied as desired. In this type of holder the clip 24 is omitted and the handle 11 is provided with a chain 26, which latter may be attached at its opposite end to a necklace, or the like, not shown.

In the still further modified type shown in Fig. 9, the shank 12 is provided with a resilient cigarette holding member 13' which is not equipped with any stub ejecting member, but, wherefrom the stub is ejected or released by the nail of the smoker.

Manifestly, therefore, the cigarette holder of the present invention is extremely simple, durable, compact and economical in construction, is reliable and efficient in use, will not readily get out of order, is adapted to restrainingly engage the cigarette at any selected or desired point thereon, and as will

be obvious from the foregoing and by referring to Fig. 8 of the accompanying drawings permits of the cigarette being placed directly in the mouth of the smoker, which latter feature is extremely important and also highly desirable.

While I have herein shown and described the invention with sufficient detail to enable those skilled in the art to understand the mode of construction and the principles involved, it is to be understood that there is no intentional limitation herein to the specific form and precise details of construction herein disclosed, except as expressly defined by the appended claims, and that various modifications of said construction may be resorted to without departing from the invention, or the benefits derivable therefrom. I also desire to have it understood that certain features of the invention herein disclosed may be employed in other combinations than those shown and described.

Having thus fully described my invention, what I claim as new and desire to secure by Letters Patent is:

1. In a cigarette holder, in combination, a stem, a hook-shaped cigarette holding member secured to said stem, and means for ejecting cigarette stubs therefrom.
2. In a cigarette holder, in combination, a stem, a resilient hook-shaped cigarette holding member secured to said stem, and flexible means for ejecting cigarette stubs therefrom.
3. In a cigarette holder, in combination, a stem, a hook-shaped cigarette holding member secured to said stem, and a flexible member normally conforming to the shape of said holding member for ejecting cigarette stubs therefrom.
4. In a cigarette holder, in combination, a stem, a resilient hook-shaped cigarette holding member secured to said stem, said member being relatively narrow and slightly concavo-convex in cross-section, and a flexible wire member rigidly secured at its outer terminal to the outer end portion of said holding member and normally seating within the concavity thereof for ejecting cigarette stubs therefrom.
5. In a cigarette holder, in combination, a stem, a tubular shank mounted upon one end thereof, a hook-shaped cigarette holding member secured to the outer end of said shank, and means mounted within said shank and co-acting with said member for ejecting cigarette stubs therefrom.
6. In a cigarette holder, in combination, a stem, a tubular shank mounted upon one end thereof, a hook-shaped cigarette holding member secured to the outer end of said shank, and a flexible cigarette stub ejecting member normally conforming to the shape of said holding member and extending at its inner end within said shank for manual actuation by the smoker.
7. In a cigarette holder, in combination, a stem, a tubular shank mounted upon one end thereof and having a longitudinally disposed slot formed therein, a resilient hook-shaped cigarette holding member rigidly secured to the outer end of said shank, and a flexible wire cigarette stub ejecting member rigidly secured at its outer terminal to the outer end of said holding member having its outer half adapted to normally conform to the shape of and abut the inner face of such holding member, and having its inner half adapted to extend within said tubular shank in co-axial relation thereto, the material of said ejecting member being bent at right angles adjacent its inner terminal to project through said longitudinally disposed slot for manual actuation of such ejecting member by the smoker.

In testimony whereof I affix my signature.

ALICE M. NURNBERG.
